GAME BOARD

Perry J. Grant, Pacific Palisades, Calif., assignor to
Reuben Klamer, doing business as Reuben Klamer
Associates, Beverly Hills, Calif.

Filed May 8, 1970, Ser. No. 22,890

Term of patent 14 years

Int. Cl. D21—01

U.S. Cl. D34—5

FIG. 1 is a perspective view of the game board;
FIG. 2 is a front view thereof;
FIG. 3 is a side view thereof;
FIG. 4 is a top plan view thereof; and
FIG. 5 is a bottom plan view thereof.
For convenience, FIGS. 1 and 2 show only a portion
of the holes in the flat surface of the game board which
in fact extend over the entire flat surface.

I claim:

The ornamental design for a game board, as shown and
described,
